UNITED STATES PATENT OFFICE.

GEORGE L. EDGERTON, OF GOLDSBORO, NORTH CAROLINA.

DESIGN FOR A SALT BRICK.

56,913.

Specification for Design.

Patented Jan. 18, 1921.

Application filed July 16, 1919. Serial No. 311,365. Term of patent 14 years.

To all whom it may concern:

Be it known that GEORGE L. EDGERTON, a citizen of the United States, residing at Goldsboro, in the county of Guilford and State of North Carolina, have invented a new, original, and ornamental Design for a Salt Brick, of which the following is a specification.

Referring to the drawings:

Figure 1 is a perspective view of a salt brick embodying my new design;

Fig. 2 is a side elevation of the same; and
Fig. 3 is an end view.

I claim:

The new, original and ornamental design
for a salt brick, substantially as shown.

In testimony that I claim the foregoing
as my own I have hereto affixed my signature.

GEORGE L. EDGERTON.
